UNITED STATES PATENT OFFICE.

HUBERT KRANTZ, OF BROOKLYN, NEW YORK.

HOUSING.

No. 873,872.

Specification of Letters Patent.

Patented Dec. 17, 1907.

Application filed January 26, 1907. Serial No. 354,187.

To all whom it may concern:

Be it known that I, HUBERT KRANTZ, a citizen of the United States, residing at Brooklyn, New York, have invented certain new and useful Improvements in Housings, of which the following is a clear, full, and exact description.

This invention relates to housings for the terminals of electric conductors, particularly where connections are to be made to the base blocks, of bus-bars, knife edge switches and like devices, although it is also applicable to other general uses.

The object of the invention is to provide a cheap satisfactory readily attachable and detachable housing which will afford good connection in use between the binding post or other binding means, and further to provide one which will be incapable of rotation in fastening the housing in place without marring the surface to which it is attached, a still further object being to properly guide the conductor at right angles to the edge of the block or like body, so that, a board having many connections on a parallel line will present a neat appearance, all wires leaving the respective binding post on substantially parallel lines.

My invention will be pointed out in the claims.

In the drawings, Figure 1 is a blank from which my improved housing may be made; Fig. 2 is a perspective inverted view of a housing ready for use; Fig. 3 is a perspective view showing the binding post, conductor housing and thumb screw as they may be placed in position; and Fig. 4 is a perspective view of a connection as made by my improved device.

The blank B and housing H are of horse-shoe or U shape and provided with a central opening O communicating with the space between the legs. A rim R is provided around part of the two straight sides of the blank B and it extends around the curved side. The blank B is forced up into the shape of Fig. 2 to form the housing with a roof portion 1, making a ledge around a cen-

tral opening 2 communicating with the exterior by a passage 3 between the legs of the horseshoe or U. The rim R of the blank forms a low wall 4 around the two straight sides 5 and 6 and around the curved side 7, preferably of less height than the conductor 20 when barred of its insulation. The ends 55 of the horseshoe or U are turned up to form an end wall of two projecting lugs 8, 9 on each side of the passage 3 and they are preferably of greater height than the wall 4, for a reason to be now described.

In Figs. 3 and 4 I have shown a block 10 and a longer strip 11, respectively. Each are provided with a stationary threaded binding stud 12 over which the conductor 20 may be inserted if previously formed into a loop, as shown, or around which it may be coiled. The housing H is then slipped over the loop with the lugs 8 and 9 overlapping the edge of the block 10 or strip 11, so that the binding thumb nut 13 may be threaded 70 into place as shown in Fig. 4.

Although I have shown a stationary threaded shank and a detachable thumb nut, it will be obvious that other well known binding posts may be used.

What I claim is:

1. A housing for electric conductors comprising a roof portion and side walls, provided with an opening through the roof portion and between the side walls adapted to 80 permit the housing to be transversely removed from a binding post.

2. A housing for electric conductors comprising a roof portion and side walls, provided with an opening through the roof portion and between the side walls adapted to 85 permit the housing to be transversely removed from a binding post, and turned-over lugs at the end of said walls depending below the edge thereof.

Signed at Brooklyn, N. Y., this 24th day of January, 1907.

HUBERT KRANTZ.
